UNITED STATES PATENT OFFICE.

CONRAD FRIEDRICH CHRISTIAN LOHMAN, OF NORTHCOTE, VICTORIA.

ROTARY MOTOR.

SPECIFICATION forming part of Letters Patent No. 606,563, dated June 28, 1898.

Application filed July 29, 1897. Serial No. 646,364. (No model.)

To all whom it may concern:

Be it known that I, CONRAD FRIEDRICH CHRISTIAN LOHMAN, engineer, a subject of the Emperor of Germany, residing at No. 13 5 Andrew street, Northcote, near Melbourne, in, the British Colony of Victoria, have invented an Improved Rotary Motor to be Driven by Steam or other Motive Fluid, of which the following is a specification.

10 The main object of this invention is to provide a rotary motor which can be worked by steam, compressed gas, or other motive fluid, which will develop a maximum amount of power with a minimum of cost, and which will 15 utilize certain novel principles of action and reaction, as hereinafter described.

In order to facilitate a clear understanding of the invention, I will describe it by reference to the accompanying drawings, where- 20 in—

Figure 1 is a vertical central section of a motor constructed according to this invention. Fig. 2 is a side elevation, and Fig. 3 is a horizontal section on line 3 3, Fig. 1, while 25 Fig. 4 is a vertical section of a certain part of the motor.

The same letters of reference indicate the same parts in all the figures.

A represents a horizontal rotating disk having a number of radial inclined blades B around its periphery. This disk may be cup-shaped, as shown in Fig. 1, or its upper surface might be inclined, so as to form a conical disk, although the shape shown is preferable. This disk A is mounted upon a spindle a, which rests upon a vertically-adjustable cone a' in the center of a second horizontal rotating disk C, and said disk A is also provided with an upwardly-extending spindle or shaft a², which is steadied in gun-metal or other bearings a³, carried by a casting D, forming the main frame or support of the motor.

The upper disk A can be adjusted relatively 45 to the lower one C by means of a conical-ended set-screw E passing into the central boss c' of the lower disk C and arranged so that its conical end e bears against the under side of and thus supports the conical stud a', 50 carrying the spindle a of the disk A. By turning this set-screw E in the required direction it will be obvious that said disk A can

be raised or lowered with great exactitude, and thus the adjustment between the two disks can be readily made.

The lower disk C, like the upper one, has a number of radial inclined blades F, which are, however, set at an opposite angle to the blades B, as shown in Fig. 4, and which, moreover, are made larger—that is, they occupy a space equal to two or more of the blades B. They are also each provided with a small hole or recess f, as shown.

The disk C is mounted upon a vertical spindle G, which passes through a gun-metal or other bearing g, carried by the casting D, and which rests upon a point-bearing g', whereby it can be adjusted to suit requirements.

An annular channel or chamber h is formed on the under side and around the center of the disk C, and this chamber is provided with a stuffing-box h', whereby a fluid-tight joint is provided around an encircling sleeve h², projecting up from the bearing g. From this chamber h one or more pipes H is or are led 70 to one of the radial blades F, and is formed with an upwardly and rearwardly inclined discharge or delivery port h³, as shown in Fig. 4, so that the current of steam or compressed gas will be delivered therefrom between the radial blades B of the upper disk A.

The supply of steam or other motive fluid to the chamber h may be through the inlet-pipe H'.

A chimney I is fitted around the upper portion of the motor by being bolted down firmly to the frame or casting D and extends upwardly for a sufficient height to cause a draft as the motor is working.

The operation of the invention is as follows: 90 The two disks A and C having been carefully adjusted so that they revolve clear of each other with the least possible space between them, steam, compressed gas, or other motive fluid is supplied through the pipes H' and H 95 to the inclined discharge-ports h³, whereby such fluid will be directed between the blades B of the disk A, thus causing same to rotate at a high speed. The effect of the heat and the fluid-current generated will be to rotate the disk C in the opposite direction, thus using a certain amount of power that would be otherwise wasted.

The rotary motion of the disks A and C can

be utilized in many different ways—as, for instance, by means of belts leading off pulleys on the spindles G and a^2 , it being merely necessary in the event of movement in one direction only being required to use a crossed belt on one of the pulleys, as will be readily understood.

The action of the motor will be greatly assisted by the draft in the chimney I, and under some circumstances it might be practicable by increasing the size of the disks A and C together with that of said chimney to utilize this draft for driving the motor.

Another application of the invention for electrical purposes might be to use the one disk as a rotating field and the other as an oppositely-rotating armature, the current being led off from between the two disks.

Having now particularly described and ascertained the nature of my said invention and in what manner the same is to be performed, I declare that what I claim is—

1. In a rotary motor the combination with the frame of a rotatable disk journaled there-in having inclined radial blades around its periphery, a complemental rotatable disk independently journaled in said frame having radial blades around its periphery inclined oppositely to the blades on said first-named disk and having recessed delivery-ports there-in, an annular chamber provided on the outer face of said complemental disk having an in-

let for the motive fluid, pipes connecting said chamber with the delivery-ports of said radial blades, and a chimney encircling the 35 disks and extending upward therefrom and closed at its lower end to communication with the outer air except through the spaces between the two sets of blades, substantially as described.

2. In a rotary motor, the combination with the frame of two shafts independently mounted therein in line with each other, means for vertically adjusting said shafts, a rotatable disk carried by each shaft having radial inclined blades around its periphery, one of said disks being located beneath the other in operative relation thereto and having its blades oppositely inclined from the blades of the upper disk and provided with recessed 45 delivery-ports, an annular chamber provided on the outer face of the lower disk having an inlet for the motive fluid, pipes connecting said chamber with the delivery-ports of said radial blades, and a chimney encircling the 50 upper disk and extending upward therefrom and closed at its lower end to communication with the outer air except through the spaces between the two sets of blades, substantially as described.

CONRAD FRIEDRICH CHRISTIAN LOHMANN.
